UNITED STATES PATENT OFFICE.

OSWALD B. CARSON, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION.

DESIGN FOR A DISPLAY DEVICE.

47,781.

Specification for Design.

Patented Sept. 7, 1915.

Application filed July 1, 1915. Serial No. 37,599. Term of patent 3½ years.

To all whom it may concern:

Be it known that I, OSWALD B. CARSON, a citizen of the United States, residing at Southbridge, in the county of Worcester and State of Massachusetts, have invented a new and original ornamental Design for a Display Device, of which the following is a specification, reference being made to the accompanying drawings, forming a part thereof.

In the accompanying drawing the figure is a perspective view of a human hand upon

a base for holding any preferred article to be displayed, showing my new design.

I claim:

The ornamental design for a display device as shown.

In testimony whereof, I affix my signature in the presence of two witnesses.

OSWALD B. CARSON.

Witnesses:

H. H. STYLL,
CARROLL BAILEY.
